UNITED STATES PATENT OFFICE.

ISADORE GOLDMAN AND LEO SCHLESINGER, OF SAN FRANCISCO, CALIFORNIA.

DISPLAY-BOX.

1,367,248.

Specification of Letters Patent. Patented Feb. 1, 1921.

Application filed September 2, 1920. Serial No. 407,733.

To all whom it may concern:

Be it known that we, ISADORE GOLDMAN and LEO SCHLESINGER, citizens of the United States, residing in the city and county of San Francisco and State of California, have invented new and useful Improvements in Display-Boxes, of which the following is a specification.

Our invention relates to improvements in display boxes wherein a window is provided in one wall to display the contents of the box and a transparent member is slidably mounted adjacent said window and hingedly connected to the adjacent portion of the cover of said box whereby said window may be raised to provide access to the interior of said box when said cover is raised.

The primary object of the present invention is to provide a new and improved display box;

A further object of the invention is to provide a new and improved display box for attractively displaying the contents thereof which box shall be simple and cheap in construction and operation and having a maximum efficiency;

A still further object is to provide a new and improved device of the character described adapted to facilitate removal of the lower portion of the contents thereof, such as shirts, or other merchandise stowed in separate layers, without disturbing upper portion of said contents, and also without being required to remove the box from the shelf when other boxes are stored on top thereof.

We accomplish these and other features by means of the improved device disclosed in the drawings forming a part of the present specification wherein like characters of reference are used to designate similar parts throughout the said specification and drawings, and in which:

Figure 1 is a partly broken perspective view of our improved display box, disclosing the cover and the transparent element partly raised to provide access to the interior of said box;

Fig. 2 is a perspective view of the box in a closed position; and

Fig. 3 is a broken side elevation, partly in section, disclosing the details of the invention.

Referring to the drawings the numeral 1 is used to designate in general a box of any suitable size, shape and dimensions hav-

ing a partition 2 arranged adjacent to and parallel with one wall of the box 1 to form a compartment 3, said wall and partition having registering windows therein to provide access to the interior of the box, the space between the adjacent walls of said partition 2 and wall forming vertically disposed grooves at the sides of said windows within which compartment or grooves is slidably mounted a transparent member 4 hingedly connected, by means of any flexible tape 6 or in any other suitable and efficient manner, to the adjacent portion or edge of a suitable cover 7 mounted upon the box, so that when the said adjacent edge or portion of said cover 7 is raised the transparent member 4 will also be raised to open said registering windows to provide access to the interior of the box 1 and the contents thereof.

The advantage of this novel arrangement is that where one or more boxes are stored on top of each other on a display shelf or the like access may be had to the contents of a lower box without removing the upper boxes but by merely raising the cover of the lower box slightly and the boxes resting thereon, until the transparent member 4 is raised a sufficient distance to permit withdrawal of the required contents of the box 1.

A further advantage of this novel arrangement is that where shirts 8 or other similar goods are arranged in layers, as disclosed in Fig. 3 of the drawings, one of the lower shirts may be removed by raising the cover 7 and transparent member 4 hingedly connected thereto until the lower edge of said member 4 just clears the required article when said article may be removed and the member 4 will then serve as a stop to prevent withdrawal of the upper portion of the contents of said box 1.

Therefore it is obvious that practically all portions of the contents of the box will be visible and only that portion of the contents removed that may be required without removing the cover 7 entirely from the box, or without removing the upper contents of the box to render the lower contents accessible.

Having thus described our invention what we claim as new and desire to secure by Letters Patent is:

1. A display box having a window in one wall thereof; a suitable cover mounted upon the box; and a transparent member ar-

ranged to close said window and hingedly connected to said cover whereby said member may be raised to provide access to the interior of said box through the window therein when the side of said cover adjacent

5 said transparent member is raised.

2. A display box having a window in one wall thereof and vertically disposed grooves arranged adjacent the sides of said window; 10 a suitable cover mounted upon the box; and a transparent member slidably mounted within the grooves and hingedly connected to the adjacent edge of the cover whereby said window may be removed to provide access to said box through said window when the edge of said cover adjacent said member is raised.

3. A display box having a partition adjacent to and parallel with one of the walls thereof to provide a compartment, said partition and wall having registering windows therein; a suitable cover mounted upon the box; and a transparent member slidably mounted within the compartment to close the registering windows and hingedly connected to the adjacent portion of the cover whereby said member may be raised to provide access to the interior of said box through said registering windows when the adjacent edge of the cover is raised. 25 30

In witness whereof we hereinto set our signatures.

ISADORE GOLDMAN.
LEO SCHLESINGER.
